UNITED STATES PATENT OFFICE.

ALBERT D. HEYL, OF PHILADELPHIA, PENNSYLVANIA.

AUTOMATIC LOWERING MACHINE.

1,386,253.

Specification of Letters Patent. Patented Aug. 2, 1921.

Application filed November 14, 1919. Serial No. 338,047.

To all whom it may concern:

Be it known that I, ALBERT D. HEYL, a citizen of the United States, residing in the city and county of Philadelphia, State of Pennsylvania, have invented a new and useful Automatic Lowering-Machine, of which the following is a specification:

My present invention comprehends a novel automatic lowering machine, wherein a gig or receptacle for the material is counterbalanced by means of a cable passing over a sheave and connected to a counterbalance or weight, the weight being heavy enough to cause the receptacle when empty to be turned to the top of the machine.

The lowering of the receptacle is accomplished by the weight of the material to be lowered, which when placed in the receptacle, overcomes the weight of the counterbalance.

In practice, the points at which the material is received and discharged are variable, as well as fixed, and therefore provision must be made to cause the receptacle to be brought to rest at the desired point for receiving and at the desired point for discharging the material.

Furthermore, in piling material, the point of discharge varies as the pile increases in height, while in unpiling the material, the receiving point will vary as the height of the pile is decreased.

In accordance with my present invention, I have devised a movable pneumatic controlling mechanism to cushion the travel and bring the gig to rest at any desired point.

With the above in view, my invention further comprehends a novel construction of an automatic lowering machine provided with means to automatically bring the receiving receptacle to rest at any desired point in its travel, and novel means for adjusting the controlling mechanism, whereby the point of delivery may be varied in accordance with requirements met with in practice.

It further consists of a novel construction of a shock absorbing and cushioning device.

It further consists of a novel construction and arrangement of a plunger, novel guiding means, and a novel construction and arrangement of cushioning devices which may be positioned at any desired point.

Other novel features of construction and advantage will hereinafter more clearly appear in the detailed description of the invention.

For the purpose of illustrating my invention, I have shown in the accompanying drawings, a typical embodiment of it, which in practice will give satisfactory and reliable results. It is, however, to be understood that the various instrumentalities of which my invention consists can be variously arranged and organized and that the invention is not limited to the precise arrangements and organization of these instrumentalities as herein set forth.

Figure 1 represents in side elevation an automatic lowering machine embodying my invention.

Fig. 2 represents in sectional elevation a portion of the controlling mechanism in the position the parts appear when the receiving receptacle is at the lower end of its travel.

Fig. 3 represents in sectional elevation a portion of the controlling mechanism in the position which it assumes when the receiving receptacle is at the upper end of its travel.

Fig. 4 represents a section on line 4—4 Fig. 2.

Fig. 5 represents a section on line 5—5 Fig. 2.

Fig. 6 represents in sectional elevation the receiving receptacle and its adjuncts, in the position it assumes when discharging.

Fig. 7 represents in perspective the counterbalance employed.

Similar numerals of reference indicate corresponding parts.

Referring to the drawings, 1 designates a base or foundation from which extends upwardly the vertical guides 2 on which the gig or receptacle for the material 3 is guided in the usual manner. The guides 2 at their upper ends are connected to the upper cross-bar 4, on which are mounted the journals 5, which carry the sheave 6 around which passes a cable 7, one end of which is connected to the gig or receptacle 3, while its opposite end is connected to a counterbalance 8. 9 designates the stop bar which is adjustably clamped to the guides 2 at any desired height above the ground. This stop bar carries the cylinders 10 with which operate the pistons 11 which are carried by a bar 12 secured in any desired manner to the bottom of the gig.

The construction of the counterbalance 8 is best seen in Fig. 7 from which it will be understood that this counterbalance consists

of a solid or apertured plunger 13 having at its upper end an eyelet to which the cable 7 is connected. The plunger 13 is provided at its upper end with the packing rings 14 and at its lower end with the packing rings 15. Intermediate the ends of the plunger are located the laterally extending guide plates 16, which are guided on the webs 17 of the T-shaped bar 18, which are supported 5 on the foundation 1 and connected to the upper cross bar 4. The webs of the T bars 18 are provided at desired intervals with the apertures 19, in order that the upper cylinder 20 and the lower cylinder 21 may 10 be positioned at any desired height.

Each cylinder 20 and 21 is constructed in a similar manner, except that the upper cylinder 20 is apertured as at 22 in order that the cable 7 may pass therethrough. The 15 cylinder 20 has its upper end closed and its lower end opened and is provided intermediate its ends with the ports 23. The cylinder 20 is provided with flanges 24, see Fig. 4, and these flanges 24 at each side are 20 guided on the web 19 of a vertical guide 18. The upper cylinder 20 is secured in its adjusted position by means of fastening devices 25, such as, for example, the bolts and nuts seen in Fig. 4. The lower cylinder 21 25 has its upper end open and its lower end closed and is provided with ports 26, see more particularly Fig. 3. This cylinder 21 is provided with flanges similar to those of the cylinder 20 and the lower cylinder is 30 secured in its adjusted position by means of fastening devices 27 passing through said flanges and apertures 19 in the vertical guides 18.

Referring now more particularly to Figs. 40 1 and 6, it will be seen that at one side of the lower cushioning device standards 28 are provided, which have secured to them at their upper end a cross-bar 29, to which is secured a spring 30 by means of the straps 31, so that a plurality of bow-shaped springs are provided against which the pivoted bottom 32 of the gig 3 will strike when the gig reaches its position to discharge the material from it, it being readily understood from 45 Fig. 6 that as soon as the pivoted bottom 32 is moved into the position shown in Fig. 6, that the material thereon, such as ice, will be discharged into the chute 33. The weight of the counterbalance 8 is such 50 that when the gig is not loaded, it will automatically be moved upwardly.

The operation will now be readily understood, and is as follows:—

The cylinder 20 is adjusted at such height 60 on the vertical guides 18 that the gig 3 when moved downwardly will stop at a desired height from the base 1. The cylinder 21 is adjusted at such height that the gig 3 when unloaded will automatically return 65 and come to rest at a desired height.

It will be seen that when the gig 3 is moved downwardly, the upper end of the plunger 8 which acts as a piston will enter the upper cylinder 20, so that the air compressed by the upper piston will pass slowly 70 out through the ports 23. When the gig 3 moves upwardly, the plunger 8 moves downwardly and the piston formed by the packing 15 will pass into the air cylinder 21.

It will be apparent that in accordance 75 with my present invention, the points at which the material is received and discharged may be varied, in accordance with conditions and requirements met with in practice, and that the travel of the gig both 80 in its upward and in its downward movement is controlled so that it can be brought to rest in either of such movements at any desired point.

If deemed necessary, I may provide a 85 shock absorbing device in order to cushion the upward stroke of the gig 3. The vertical guides 2 have adjustably secured to them the cross bar 34, which carry the plungers 35, which coöperate with the dash pot cylinders 36 carried at the upper end of the gig 3.

It will be understood from the foregoing that in accordance with my present invention, I employ a pneumatic control for automatically stopping the gig at any desired point in its upward or downward travel. This automatic controlling mechanism may be employed to coöperate directly with the gig or it may be employed in such a manner 95 that it forms a part of the counterbalance and it is therefore to be understood that one or the other of the pneumatic controlling devices may be dispensed with. The stop bar 9 which carries the cylinder 10 is adjustably clamped to the guides 2 and the stop bar 34 is adjustably clamped to the guides 2 in a similar manner so that the gig will be brought to rest at any desired point 100 in its upward travel and at any desired point in its downward travel.

It will now be apparent that I have devised a new and useful construction of an automatic lowering machine which embodies the features of advantage enumerated 115 as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:—

1. An automatic lowering machine, comprising a frame-work having gig guides, a 130

gig coöperating with said guides, an upper and a lower dash pot for said gig, a sheave carried by said frame-work, a cable connected with said gig and passing over said 5 sheave, a counterbalance comprising a plunger having a piston head at its upper and lower end, one end of said counterbalance being connected to said cable, guide flanges on said counterbalance, vertical guides with 10 which said flanges coöperate, an upper cylinder having one end closed and its other end open and provided with vents and adjustably secured to said guides, and a lower cylinder provided with vents and having its 15 upper end open and its lower end closed and adjustably secured to the counterbalance guides.

2. In an automatic lowering machine, a gig, a counterbalance operatively connected 20 with it to raise it when unloaded, guide forming angle bars coöperating with said counterbalance, an upper cylinder, means to

secure it in adjusted position on said angle bars, a lower cylinder, and means to secure it in adjusted position on said angle bars. 25

3. In an automatic lowering machine, a gig having a movable bottom, a counterbalance operative to raise the gig when it is unloaded, means to automatically actuate said bottom when the gig reaches the limit of its 30 downward travel, guiding means for said counterbalance, and a cushioning device for said counterbalance adjustably secured to said means to arrest the counterbalance, and thereby the downward movement of said 35 gig, whereby the lower limit of travel of the gig can be varied to effect the automatic discharge of its load at any desired distance from its loading point.

ALBERT D. HEYL.
